INVENTOR
MAXWELL C. FRANK
by *A.S. Paré* atty.

UNITED STATES PATENT OFFICE.

MAXWELL C. FRANK, OF PIEDMONT, CALIFORNIA.

ATTACHMENT FOR ELECTRIC-LIGHT SWITCHES.

1,207,155.

Specification of Letters Patent.

Patented Dec. 5, 1916.

Application filed November 29, 1915. Serial No. 63,916.

To all whom it may concern:

Be it known that I, MAXWELL C. FRANK, citizen of the United States, residing at Piedmont, county of Alameda, State of California, have invented certain new and useful Improvements in Attachments for Electric-Light Switches, whereof the following is a specification.

This invention relates to luminous attachments for electric light switches and the like.

The object of the invention is to provide an attachment which may be applied to wall switches of electric lights, whether push button or turn button switches, or otherwise, for the purpose of rendering the same visible at night or in dark places and can be easily found.

To this end, the invention consists in a vacuum cup, of rubber or equivalent material, which may be applied to the button of the switch, or to the switch plate or other object adjacent thereto, said vacuum cup being provided with a luminous cap, whereby the switch button may be easily seen and found when it is desired to turn on the light.

In the accompanying one sheet of drawing I have illustrated for the purpose of this application, my invention in a number of views showing its use and advantages.

In the drawing:—Figure 1 is a plan or top view showing a wall push comprising two buttons, one to turn on the light, and one to turn it off, with one of my attachments applied to the button base adjacent to the same. Fig. 2 is a side view of the same. Fig. 3 is a sectional view, on an enlarged scale, showing the attachment of Figs. 1 and 2 when placed against the switch base, but not yet collapsed. Fig. 4 is a similar view to Fig. 3, but showing the attachment collapsed, and firmly secured to the switch base. Fig. 5 is a similar view to Fig. 2 but showing the attachment applied to one of the push buttons instead of to the base. Fig. 6 is a partial view, similar to Fig. 5, but showing the attachment in section. Fig. 7 is a top view, showing the attachment as applied to a turn button, or snap switch. Fig. 8 is a side view of the same. Fig. 9 is a sectional view showing the attachment with a post for collapsing it, permanently attached to it.

In these figures:—1 is the base of a wall switch, carrying the "on" and "off" but-

tons 2, and secured by means of the screws 3. 4 is my attachment, applied to the base 1 adjacent to one of the buttons 2, preferably to the "on" button.

63

My attachment 4 (see the enlarged views Figs. 3 and 4) consists of the rubber vacuum cup comprising the body 5, having the thin edge 6, the concavity 7 and the stud portion 8 opposite the concavity 7. Upon the stud 65 portion 8 is secured a glass or other transparent hemisphere 9, having a luminous lining 10 on its inner surface, and having also a hole 11 in its apex. In applying the attachment 4, it is first placed 70 in the desired position, as seen in Fig. 3, and a pencil, or similar article, inserted through the hole 11 and pressed in until the vacuum cup is collapsed, as seen in Fig. 4. The cup will then adhere by virtue of the air 75 pressure upon its exterior, and the luminosity of the hemispherical or other shaped cap 9 will suffice to render the switch buttons visible. When desired an adhesive substance may be applied to the surface of the 80 concavity 7, as shown at 12, see Fig. 6, to increase its holding power.

When applied to a snap switch, or turn button, the cup 5 is commonly applied to the center of the button, as seen at 13 in 85 Figs. 7 and 8. In these figures:—1 is the base plate of the switch, applied to the wall 14, and 15 is the button. 5 is the collapsed cup, and 9 the luminous top of same.

In some cases it may be found desirable to 90 use a permanently attached port 16, see Fig. 9, to collapse the cup, instead of a pencil, as already described.

Having thus described my invention, and an embodiment of it, in the full, clear and exact terms required by law, and knowing that it comprises novel, useful and valuable improvements in the art to which it pertains, I here state that I do not wish to be limited to the precise construction and arrangement of the several parts, as herein set forth, as the same may be variously modified by a skilled mechanic without departing from the spirit of the invention as 95 claimed.

100

What I claim and desire to secure by Letters Patent of the United States, is the following, to wit:—

1. An attachment for electric light switches, comprising a collapsible vacuum cup, a luminous top of hemispherical shape, centrally secured upon the outer surface of 110

said vacuum cup, and forming a part thereof.

2. An attachment for electric light switches, comprising a rubber vacuum cup, 5 provided with a central stud portion, a transparent hemispheric top secured to said stud portion, having luminous lining on its inner surface, and a hole in its apex adapted for the insertion of means for collapsing said 10 vacuum cup.

3. An attachment for electric light switches, comprising a collapsible cup, a luminous hemispheric top mounted upon 15 said collapsible cup, and means for securing said top thereon, a central hole on said top, and means inserted in said hole adapted to collapse said cup.

4. An attachment for electric light switches, comprising a rubber vacuum cup, 20 provided with a stud portion, a central integrally formed post projecting therefrom,

and adapted to collapse said vacuum cup, a luminous top secured to said stud portion, and provided with a central hole for said post.

5. As a new article of manufacture, an attachment of the character described comprising a vacuum cup provided with an adhesive applied to the bearing side thereof, a luminous top surmounted and secured to the opposite side of said cup, and said top having a central hole adapted for central direct application means for securing said cup in position.

In testimony that I claim the foregoing I 35 have hereto set my hand, in the presence of two witnesses, this 10th day of November, 1915.

MAXWELL C. FRANK.

Witnesses:

R. MAUDE WOLFE,
L. A. ALVES.
